UNITED STATES PATENT OFFICE.

FRANK LIMER, OF McWHORTER, WEST VIRGINIA.

CLAW-BAR.

1,131,393.

Specification of Letters Patent.

Patented Mar. 9, 1915.

Application filed April 22, 1914. Serial No. 833,731.

To all whom it may concern:

Be it known that I, FRANK LIMER, a citizen of the United States, residing at McWhorter, in the county of Harrison and State of West Virginia, have invented certain new and useful Improvements in Claw-Bars, of which the following is a specification, reference being had to the accompanying drawings.

10 This invention relates to certain improvements in claw bars and has relation more particularly to a device of this general character especially designed and adapted for use for withdrawing spikes, drift bolts and similar fastening members; and an object of the invention is to provide a device of this general character having novel and improved means whereby the force exerted upon the operating lever not only tends to withdraw the fastening member but also causes the gripping jaws to firmly engage the same.

25 The invention also has for an object to provide a novel and improved device of this general character including relatively movable gripping jaws which will be brought into clamping engagement with the fastening member when the operating lever is depressed and reversely moved when such 30 lever is lifted or elevated.

35 A further object of the invention is to provide a device of this general character including relatively movable gripping jaws pivotally engaged with an operating lever and provided with novel and improved means whereby such gripping jaws are held against relatively independent rotation about their pivotal connections with the lever.

40 The invention consists in the details of construction and in the combination and arrangement of the several parts whereby certain important advantages are attained and the device is rendered simpler, less expensive and otherwise more convenient and 45 advantageous for use, all as will be herein-after more fully set forth.

The novel features of the invention will be carefully defined in the appended claim.

50 In order that my invention may be the better understood, I will now proceed to describe the same with reference to the accompanying drawings, wherein—

55 Figure 1 is a fragmentary elevational view of a claw bar constructed in accordance with an embodiment of my invention, one of the clamping members or nuts of the pivotal

connection being omitted; Fig. 2 is a view somewhat similar to Fig. 1 but with one of the jaws omitted and certain of the parts shown in section; Fig. 3 is a sectional view 60 taken substantially on the line 3—3 of Fig. 2; Fig. 4 is a sectional view taken substantially on the line 4—4 of Fig. 2; Fig. 5 is a sectional view taken substantially on the line 5—5 of Fig. 2; and Fig. 6 is a view in 65 perspective, detached, of one of the clamping jaws herein included.

As disclosed in the accompanying drawings, 1 denotes a claw divided longitudinally to afford the companion jaws 2—2. The 70 jaws or complementary parts 2 of the claw are similarly formed and have depressions in their opposed faces midway of their ends, which unitedly provide a recess or mortise 3 in which is fitted the lower end of the operating lever 4. The front ends of the jaws 2 are cut-away at their inner sides forming a depression or cavity 5 to receive the head of a spike, bolt or the like, to which the implement is fitted, when it is desired to draw 80 the same. It will also be observed that the depression or cavity 5 provides the cutting or biting edges 6 which are adapted to impinge or penetrate the fastener sufficiently to draw the same without coaction with the 85 head thereof, as is believed to be self-evident to those skilled in the art to which my invention appertains. The under surfaces of the jaws 2 have their forward portions rounded, as indicated at 7, so that such jaws 90 may serve to afford a fulcrum on which the device, as a whole, will rock in order that requisite upward movement may be created to effect a draw of the fastening member.

As herein disclosed, the operating lever 4 95 is pivotally engaged with the jaws 2—2 through the medium of the transverse bolt 8 directed through registering openings produced in such jaws and the lower extremity of the lever 4, the openings 9 in the jaws 100 being of a diameter in excess of the diameter of the bolt so that such jaws are capable of a relative lateral movement so that the knife edges 6 thereof may be caused to be brought in requisite engagement with the 105 fastening member to be drawn.

The operating lever 4 in close proximity to its pivotal portion has its under longitudinal face formed into the wedge portion 10 which is normally positioned between the 110 opposed faces of the rear ends of the jaws 2 and as the operating lever is depressed

- such wedge portion 10 serves to impart the requisite lateral movement to the jaws 2 as to assure the proper engagement of such jaws with the fastening member to be withdrawn, as is believed to be clearly obvious. The upper portion of the lever member adjacent its lower extremity is provided with a forwardly directed wedge member 11 adapted to be received between the opposed faces of the forward portion of the jaws 2 and causing the same to separate automatically when the operating lever 4 is lifted or elevated, and the extent of separation of such engaging end portions of the jaws 2—2 is limited by contact of the shoulders 12—12 provided on the operating lever 4 with the adjacent upper portions of the jaws 2, as is believed to be clearly shown in the accompanying drawings.
- 20 In practice I have found that it is particularly desirable that the jaws 2 be maintained against relative independent rotation about the pivotal bolt 8 and, as herein disclosed, the rear or heel portion 14 of one of the jaws 2 is provided with a transverse opening 15 adapted to loosely accommodate the finger or pin 16 projecting laterally from the opposed face of the rear or heel portion 17 of the complementary jaw 2.
- 30 To further prevent relative independent movement of the jaws 2—2 about the pivotal bolt 8, I also find it of advantage to provide a forward portion 18 of one of the jaws 2 with a lateral finger or projection 19 adapted to be loosely accommodated within the lateral groove or recess 20 produced in the forward portion 21 of the complementary jaw 2 and, as herein disclosed, such recess or groove 20 is produced in the forward wall of the recess of such jaw, which serves to afford the mortise 3. It is also to be observed that the projections or fingers 16 and 19 are reversely directed as are the opening 15 and recess or groove 20.
- 45 From the foregoing description, it is

thought to be obvious that a claw bar constructed in accordance with my invention is of an extremely simple and comparatively inexpensive nature and is particularly well adapted for use by reason of the convenience and facility with which it may be assembled and by reason of the effectiveness with which it performs its functions, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

A device of the character described comprising an operating lever, gripping jaws pivotally connected intermediate of their lengths with the lower extremity of said lever and capable of relative lateral rocking movement, one of said jaws being provided with a lateral recess in its inner face in advance of its pivotal connection with the lever, a laterally directed inwardly disposed finger carried by the coacting jaw in advance of its pivotal connection with the lever and loosely accommodated within the lateral recess of the first named jaw, one of said jaws rearwardly of its pivotal connection with the lever being provided with a transverse opening, an inwardly disposed laterally directed finger carried by the adjacent jaw and directed within said opening, and means carried by the operating lever for imparting relative transverse rocking movement to the jaws in opposite directions.

In testimony whereof I hereunto affix my signature in the presence of two witnesses.

FRANK LIMER.
